UNITED STATES PATENT OFFICE.

JAMES D. BLAYNEY, OF TORONTO, ONTARIO, CANADA.

INTERNAL-COMBUSTION MOTOR.

1,243,691.

Specification of Letters Patent. Patented Oct. 23, 1917.

Application filed March 29, 1916. Serial No. 87,550.

To all whom it may concern:

Be it known that I, JAMES D. BLAYNEY, of the city of Toronto, in the county of York, Province of Ontario, Canada, a subject of the King of Great Britain, have invented certain new and useful Improvements in Internal-Combustion Motors, of which the following is a specification.

This invention relates particularly to internal combustion motors of the multi-cylinder type in which all the cylinders are operatively connected with the same crank and preferably rotate about the shaft, and my object is to devise an engine in which the thrust of the connecting rods during the explosion strokes of the motor is more nearly parallel to the axes of their cylinders than in the ordinary motor, and to provide in such a motor a balanced, positively actuated, slide valve system adapted for high speed operation.

I attain my object by means of the constructions hereinafter described and illustrated in the accompanying drawings in which—

Figure 1 is a side elevation partly in section of my improved motor;

Fig. 2 a longitudinal section through one of the cylinders of the motor;

Fig. 3 a plan view partly in section of one of the cylinders; and

Fig. 4 a longitudinal section through the slides of one of the valves.

In the drawings like numerals of reference indicate corresponding parts in the different figures.

I show the motor arranged so that the cylinders rotate and the crank shaft remains stationary, but the improved construction is applicable to a case in which the cylinders are held from rotation while the crank shaft rotates.

1 is the crank shaft, which is made hollow as shown for the introduction of the combustible mixture into the crank case. 2, 3 is the crank, which is common to all the cylinders. I employ a plurality of cylinders 4 equally spaced about the crank case. The crank case is preferably formed as a hollow cylinder and its axis is coincident with the axis of the crank shaft.

The curved periphery of the crank case is provided with an opening for each cylinder surrounded by a threaded collar 5. Into these collars the inner ends of the cylinders are screwed as shown. It will be noted

that the axes of the cylinders are not radial to the axis of the crank shaft as is usually the case, but are tangential to a small circle having its center in the axis of the crank shaft. The radius of this circle, it will be noted, is not quite equal to the throw of the crank.

Each cylinder is provided with a piston 6 connected by means of a connecting rod 7 with the crank 3. The result of the peculiar setting of the cylinders relative to the crank shaft is that during the explosion stroke of each cylinder the connecting rod of that particular cylinder remains much more nearly parallel to the axis of the cylinder than with the ordinary arrangement giving a much more direct and effective thrust against the crank with less side thrust on the piston.

It will be noted also that the effective leverage of the crank increases much more rapidly after the crank passes the dead center than in the ordinary construction with the axis of each cylinder intersecting the axis of the crank shaft and holds it well through the stroke. The arrangement also enables me to more easily introduce and operate slide valves for the control of the piston ports than with the ordinary radial arrangement.

The slide valves I employ are operated from the cam shafts 8 suitably journaled on the crank case and each provided with a gear wheel 9 meshing with the gear wheel 10 fast on the crank shaft. Each cylinder is provided with an inlet port 11 and outlet or exhaust port 12, and each is controlled by a similar valve. Each valve comprises two slides adapted to move independently of one another. A preferred construction is shown in which one slide 13 is formed of a rectangular frame with an opening therein and the other of two plates 14 suitably connected and embracing the frame 13. The slides are held in place by the cap 15, and suitable grooves for the reception of the slides are formed between this cap and the cylinder about the port which the valve controls.

Each slide is provided with a connecting rod 16 by which it may be operated. These connecting rods are provided at their inner ends with projections 17, preferably formed as anti-friction rollers. These projections engage the cam grooves 18 formed in a cam disk 19 secured to one of the cam shafts 8.

- It will be noted that the cam grooves are similar but are set in diametrically opposite positions so that the slides are simultaneously reciprocated in opposite directions.
- 5 The result of this is that to obtain a given valve opening the cam throw is half of what it would be if a single valve were used, so that a quick-opening of the valve to a sufficient area may be obtained with a very small throw in any one cam groove. Each cam groove is so figured that the movement of the slides takes place during a relatively small proportion of one revolution of the cam shaft, so that there is no movement of the slides when any considerable pressure exists in a cylinder.
- 10 From the construction described, it will be seen that each slide valve is completely balanced, the movements of the two parts 20 of each taking place simultaneously in opposite directions, and the slides with their operating parts being of substantially the same weight. As the valves move, the surfaces which are exposed to the hot gases 25 during the explosion stroke move up behind other surfaces during the exhaust and suction strokes, so that the valve surfaces are constantly rubbed clean and accumulations of carbon are entirely prevented.
- 15 30 If the motor is to be used with the cylinders rotating each cylinder will be provided with the usual air cooling ribs and the exhaust will be direct to the atmosphere. The combustible mixture is led from the crank case 35 to the inlet valves by means of the intake pipes 20. Each cylinder will be provided with suitable spark plug 21 for ignition. A sleeve 22 bolted to the crank case serves as a shaft for the transmission of power.
- 40 45 What I claim as my invention is:—
1. In a multi-cylinder internal combustion motor, the combination of a crank casing; a crank shaft journaled therein provided with a crank; a plurality of equally spaced cylinders set with their axes tangential to a circle having the crank shaft as a center; a piston for each cylinder; a connecting rod for each piston connecting the same with the crank; a cam shaft for each cylinder crossing the crank casing adjacent the side of the cylinder closest to a radial plane intersecting the axis of the crank shaft and parallel to the axis of the cylinder,

55 said cam shafts being geared to the crank shaft; an exhaust cam and air inlet cam on each of said cam shafts within the crank case; an inlet and an exhaust valve on the same side of each cylinder as the cam shaft and cams for such cylinder; and valve rods extending through the crank casing for operation by said cams.

60 65 70 75 80 85 90 95 2. In a multi-cylinder internal combustion motor, the combination of a crank casing; a crank shaft journaled therein provided with a crank; a plurality of equally spaced cylinders set with their axes tangential to a circle having the crank shaft as a center, each cylinder projecting into the casing; a piston for each cylinder; a connecting rod for each piston connecting the same with the crank; a cam shaft for each cylinder crossing the crank casing adjacent the side of the cylinder closest to a radial plane intersecting the axis of the crank shaft and parallel to the axis of the cylinder, said cam shafts being geared to the crank shaft; an exhaust cam and an inlet cam on each of said cam shafts within the crank case; an inlet and an exhaust valve on the same side of each cylinder as the cam shaft and cams for such cylinder; and valve rods extending through the crank casing for operation by said cams.

95 3. In a multi-cylinder internal combustion motor, the combination of a cylindrical crank casing having an opening in the curved periphery for each cylinder, said openings being equally spaced and each provided with an internally threaded collar having its axis tangential to a circle having its center in the crank shaft of the motor; and a plurality of cylinders each threaded externally and screwed into one of said collars and projecting within the crank case, the inner end of each cylinder being cut on a bevel so that the cylinder wall is shortest at the side most nearly radial to the axis of the crank shaft.

Signed at Toronto, Canada, this 21st day of March 1916, in the presence of the two 100 undersigned witnesses.

JAMES D. BLAYNEY.
